UNITED STATES PATENT OFFICE.

ANDREW B. STEWART, OF EVANSTON, ILLINOIS, ASSIGNOR TO MAX S. STEINER, OF CHICAGO, ILLINOIS.

PORTRABLE SUPPORT FOR ELECTRIC LAMPS.

Application filed April 28, 1927. Serial No. 187,231.

This invention relates to a portable and adjustable support for electric lamps which can be readily attached to a suitable support, and by means of which an electric lamp 5 may be readily adjusted and held or supported in any desired adjusted position.

The principal object of the invention is to provide a simple, economical and efficient portable adjustable support for electric 10 lamps.

A further object of the invention is to provide an improved portable support or holder for electric lamps including means for providing universal adjustability of the electric lamp, or means whereby the lamp may 15 be readily adjusted and supported or held in any desired position relatively to its support or relatively to any particular object, and adapted to enable the lamp and reflector to be 20 adjusted or tilted in any desired direction, and turned upon any desired axis in any desired direction and held in any desired adjusted position without the necessity of operating any adjusting screws or tightening or 25 releasing any clamps or similar connecting and releasing means in order to make such adjustments.

It is particularly desirable to provide an improved portable adjustable support or 30 holder for electric lamps, including means whereby the lamp may be turned entirely around or part way around in either direction on any desired vertical, horizontal or inclined axis to any desired adjusted or operative 35 position, either upright, inverted or inclined, and held in such positions of adjustment, while the support-engaging clamp of such device is detachably secured in engagement with any suitable support.

40 Other and further objects of the invention will appear from the following description and claims, and from an inspection of the accompanying drawings, which are made a part hereof.

45 The invention consists in the features, combinations, details of construction, and arrangement of parts herein described and claimed.

In the accompanying drawings—

50 Figure 1 is a view in side elevation of a portable and adjustable support for electric lamps, constructed in accordance with my invention;

55 Fig. 2 is a view in front elevation of my improved lamp support, showing the same

attached to a lamp socket, the lamp socket being shown in end elevation;

Fig. 3 is a view in side elevation of a modified form of my improved support for electric lamps, showing the same in side elevation, with the resilient support-engaging clamp upright;

Fig. 4 is a view in front elevation of the device shown in Fig. 3, showing the same attached to a lamp socket;

Fig. 5 is a perspective view in detail showing the connecting mechanism for adjustably connecting the support-engaging spring clamp with the lamp-engaging clamp, as shown in Figs. 1 and 2; and

Fig. 6 is a similar detail view of the connecting mechanism for connecting the lamp-engaging clamp with the support-engaging clamp, with the intermediate connecting ball of the one-ball type shown in Figs. 3 and 4, 75 inverted end for end.

My improved lamp support, as applied to a lamp 1 having a socket 2, bulb 3 and hood 4, is constructed as follows:

A lamp-engaging clamp 5 is provided, 80 which is, by preference, in the form of a split sleeve or flexible collar which is adapted to encircle or embrace, and to be clamped securely in frictional clamping engagement with the lamp socket 2. The lamp-engaging clamp is provided with a pair of projecting clamping arms 6, which are, by preference, spaced apart and each provided with a cup-shaped depression 7 in the outer or projecting end thereof. The cup-shaped portions of the 85 clamping arms thus form opposed relatively adjustable spaced-apart socket portions or members 8 of a socket. The socket 8 thus formed by and between said clamping arms is adapted to receive a ball 9 which is, by preference, adapted to be mounted in and in adjustable frictional engagement with said socket, and to permit universal movement and adjustment of said ball and socket relatively to each other and to permit corresponding movement and adjustment of the lamp supported by the lamp-engaging clamp and the lamp supporting device, of which said clamp forms a part.

The clamp 5 is provided with means, which 105 may be in the form of a clamping bolt or screw 10 mounted on the clamping arms 6 and extending through suitable openings in said arms, and having a nut 11 in threaded engagement with said bolt, for tightening the 110

clamp 5 upon the lamp or lamp socket and on the said ball 9. The bolt 10 and its nut thus form a single means for simultaneously tightening said clamp on the lamp socket and 5 on the ball or support on which the lamp-engaging clamp is thus adjustably mounted.

A support-engaging clamp 12 is provided which, by preference, comprises a pair of resilient clamping arms 13, 13 having crossed support-engaging ends 14, 14 bent to form gripping or clamping jaws or loops 15, 15. Said resilient clamping arms 13, 13 are connected at their opposite extremities by means of an integral loop or coil 16 which forms 10 an integral flexible connection between said clamping arms. The coil 16 is, by preference, helical and has a sufficient number of turns so that an inner lap or coil 17 is formed between the outer laps or turns of the coil, 15 thus affording sufficient freedom and extent of movement of the clamping arms, the clamping ends of which are adapted to be detachably attached to and supported in any desired position upon any convenient or suitable support. The support-engaging clamp 20 25 is thus adapted to be removably secured to any suitable support either in upright, horizontal or any desired inclined position which circumstance may require and permit.

30 A socket-forming connecting clip 18 is mounted on the coil 16, by preference, in position to extend lengthwise of the support-engaging clamp 12, and to project endwise beyond the closed end of the clamp which is 35 formed by the coil. The clip 18 may be made in one or more pieces, but is, by preference, formed in one piece and bent to form projecting clamping arms 19, 19 the outer ends of which are spaced apart and provided 40 with depressions on their inner opposed sides, thus forming cup-shaped socket portions or members 20, 20 which are adapted to receive a ball 21, or equivalent element within the socket 20 thus formed between said clamping 45 arms. The ball 21 is by preference, connected with and in fixed relation to the ball 9 already described, by means of a connecting neck or body 22, said connected balls and neck or connecting body thus forming an 50 intermediate connecting member having said connected, and preferably integral balls 21 and 9 on opposite ends of the connecting member. The socket-forming clip 18 is mounted in position to extend through and 55 embrace between the connected or integral arms 19, one or more of the laps or turns of the coil 16; and means for tightening the clamping arms 19 upon said coil and on said ball 21 is provided, said tightening means 60 being, by preference, in the form of a threaded bolt 23 mounted in and extending through suitable openings in said clamping arms 19, 19, and having a nut in threaded engagement with said bolt and adapted to enable 65 the clamping arms 19 to be simultaneously

tightened on the coil 16 and on the ball 20, or intermediate connecting member, by a single tightening means thus provided.

The intermediate connecting member comprising connected, and preferably integral 70 balls 21 and 9, and the connecting body or neck 22, is thus held in universally adjustable relation to and has universal movement with respect to both of the clamping members or clamps and socket members 5 and 18, 75 and with respect to the lamp and the support-engaging clamp respectively. The lamp and the support-engaging clamp 12, which supports said lamp, are thus connected in universally adjustable relation to each other, 80 and are adapted to be moved in any and all directions relatively to each other to any desired position or successive positions of adjustment, and are adapted to be securely held in any desired position or positions of adjustment and without requiring the turning of a screw or bolt or the manipulation of a clamp for the purpose of securing the parts in any position to which they are adapted to be adjusted relatively to each other. 90

The lamp may thus be readily moved to or adjusted and held in either upright, horizontal, depending, or inverted, or any desired inclined position while the support-engaging clamp is in any position on any 95 suitable support to which it is attached for use.

In the form of the device shown in Figs. 1, 2 and 5, the lamp and the support-engaging clamp 12 are connected in universally movable and adjustable relation, and adapted to be held in any position of adjustment, by connecting means constructed as above described. 100

In the form of device constructed in accordance with my invention, as shown in Figs. 3 and 4, the socket-engaging or lamp-engaging clamp 5, and the support-engaging clamp 12 and coil 16 are constructed in all substantial respects as already described in 105 connection with said Figs. 1, 2 and 5. But the lamp-engaging clamp and the support-engaging coil 12 are provided with ball and socket connections, or substantially universally adjustable connecting means which comprises a socket-forming clamping and connecting member or device 24 which may have 110 clamping arms 25, 25, formed either in one integral piece or in separate pieces as shown, 115 said clamping arms being adapted to extend on opposite sides of the inner coil 17, and between said inner coil and the outer laps of the coil 16, as shown in Fig. 4. When made in separate pieces, said clamping arms 25, 25 are connected by suitable means, such, for example, as headed and threaded bolts 26 and 27, having threaded nuts thereon, one of 120 said bolts being located inside of the coil and the other outside of the coil, and both being 125 mounted in and extending through suitable 130

perforations in said clamping arms, and adapted to hold the same in, preferably, fixed clamping engagement with the inner turn 17 of the coil. The clamping arms 25 may be provided at their outer separated ends either 5 with approximately flat or cup-shaped end portions 28 having openings therethrough, and may be pivotally connected or adjustably connected with an intermediate connecting member 29 comprising a ball 30 fixed to one 10 end of a connecting neck or body, the opposite end of which is provided with a head 31 which may be flat on both sides, or may have conical or convex side surface portions on 15 one or both sides adapted to engage and to be secured in adjustable frictional engagement with corresponding approximately flat, or conical or concave inner faces of the adjacent end portions 28 of said clamping arms. 20 And a bolt 32 extends through the parts 28 and 31.

The connecting member comprising the connected balls 9 and 21 and the connecting neck or body 22 may be either formed in one 25 integral piece, or stamped in two halves extending longitudinally and secured together by rivets or welding, so as to form a hollow connecting member; or the balls may be hollow or provided with an axial opening 30 through the centers thereof and fixed to the opposite ends of the connecting neck 22 which may thus extend into said balls.

The connecting member 29 comprising the ball 30 and head 31 connected by a connecting neck is adapted to be either connected 35 with the lamp-engaging clamp 5 by having the ball clamped between and in adjustable engagement with the clamping arms 6, as shown in Figs. 3 and 4, with the head 31 connected in adjustable relation to the support-engaging clamp, or to be reversed end for 40 end, as shown in Fig. 6, with the ball 30 clamped between and in adjustable frictional engagement with socket-forming arms 19 of the socket-forming clip 18 on the coil 16, and with the head 31 clamped between and in 45 adjustable relation to the projecting clamping arms 6', 6' on and, by preference, integral with the split sleeve or lamp-engaging 50 clamp or sleeve which encircles or embraces the lamp socket. The clamping arms 6' are secured to the head 31 by means of a threaded bolt 33 extending through suitable transverse openings in said connected parts 6', 6' 55 and 31, and having a nut on the threaded end of said bolt, as shown in Fig. 6.

From the foregoing description, it will be readily understood that the ball and socket connection between the intermediate connecting member and the lamp-engaging socket, including the ball 9, or the ball 30, as the case may be, and the socket members 8 on the socket 5, are movable bodily upon an axis or axes at the center of the ball 21 or at the 60 center of the head 31, where the intermediate 65

connecting member is connected in adjustable relation to the support-engaging clamp, and that the connecting means for connecting the socket-engaging clamp in adjustable relation to the support-engaging clamp, above described and shown, includes means for securing the lamp-engaging clamp, and the ball and socket which forms the connection between the lamp-engaging clamp, in any position of adjustment, and also includes means for securing the intermediate connecting member in any desired predetermined position of adjustment with respect to both the lamp-engaging clamp and the support-engaging clamp. 70 75

The socket-forming or connecting clips 18 and 24 may be secured in gripping or clamping engagement with the coil so as to provide a sufficiently tight engagement to hold said clips in any position of adjustment on the coil, but permit the adjustment of the clips upon the coil or upon an axis located at the center of the coil, to any desired predetermined position of adjustment. 80 85

I claim:

1. A lamp-supporting device of the class described, comprising a lamp-engaging clamp having a socket thereon, a support-engaging clamp comprising a pair of clamping arms provided with a coil forming a resilient connection therebetween, a clip mounted on said coil and provided with projecting clamping arms having depressions adapted to form a socket between said arms, for receiving a ball, and an intermediate connecting member comprising a pair of connected balls, one of said balls being on one end of said connecting member and in adjustable frictional engagement with the socket on said lamp-engaging clamp and forming with said socket a universal joint between said intermediate connecting member and said lamp-engaging clamp, and the other one of said balls being on the opposite end of said intermediate connecting member and in adjustable frictional engagement with said socket on said coil and forming with said socket a universal joint between said intermediate connecting member and the support-engaging clamp, and means for tightening 100 105 110 115 said sockets in adjustable frictional engagement with the balls contained therein.

2. A lamp-supporting device of the class described, comprising a lamp-engaging clamp having a socket thereon, a support-engaging clamp comprising a pair of clamping arms provided with a coil forming a resilient integral connection between said clamping arms, a clip mounted on said coil and forming a socket, an intermediate connecting member comprising a pair of connected balls, one of said balls being on one end of said connecting member and in adjustable frictional engagement with the socket on said lamp-engaging clamp and forming with 120 125 130

said socket a universal joint between said intermediate connecting member and said lamp-engaging clamp, and the other one of said balls being on the opposite end of said connecting member and in adjustable frictional engagement with the socket on said coil and forming with said socket a universal joint between said intermediate connecting

member and the support-engaging clamp, and means for tightening said sockets on said balls respectively.

Signed at Chicago, in the county of Cook and State of Illinois, this 26th day of April, 1927.

ANDREW B. STEWART.
